(57) **CLAIM**

The ornamental design for an indoor wall with built-in home appliances, as shown and described.

DESCRIPTION

FIG. 1 is a front perspective view of the indoor wall with built-in home appliances showing our new design;

FIG. 2 is a front view thereof;

FIG. 3 is a rear view thereof;

FIG. 4 is a left side view thereof where the right side view is a mirror image;

FIG. 5 is a top view thereof;

FIG. 6 is a bottom view thereof; and,

FIG. 7 shows the indoor wall with built-in home appliances in a state of use, wherein the broken line showing of the widgets are displayed on the front right upper part and depicts environmental subject matter which forms no part of the claimed design.

1 Claim, 7 Drawing Sheets
